UNITED STATES PATENT OFFICE.

CARL G. M. MILLER, OF NEWTON, MASSACHUSETTS, AND FRANK D. MASTERS, OF BOSTON, MASSACHUSETTS, ASSIGNEES TO CHASE-SHAWMUT COMPANY, OF BOSTON, MASSACHUSETTS, A CORPORATION OF MAINE.

JUNCTION-BOX.

SPECIFICATION forming part of Letters Patent No. 716,643, dated December 23, 1902.

Application filed March 2, 1901. Serial No. 49,571. (No model.)

To all whom it may concern:

Be it known that we, CARL G. M. MILLER, of Newton, in the county of Middlesex, and FRANK D. MASTERS, of Boston, in the 5 county of Suffolk, State of Massachusetts, have invented an Improvement in Junction-Boxes, of which the following description, in connection with the accompanying drawings, is a specification, like letters on the drawings 10 representing like parts.

This invention relates to junction-boxes for electric-wiring purposes, and has for its object to improve the construction of the same in several particulars, better adapting it for 15 the purposes for which it is intended; and the invention consists in details of construction as will be hereinafter specifically described and claimed.

Figure 1 shows in plan view a junction-box 20 embodying this invention. Fig. 2 is a vertical section of the same, taken on the dotted line 2 2. Fig. 3 is an under side view of the junction-box, and Fig. 4 is a detail showing a portion of the box in side elevation.

The junction-box is made as a casting, of 25 iron or any other suitable material, and consists of a circular or other-shaped shell having an end wall *a* and a side wall *b*. The end wall *a* has recesses formed in the casting on 30 both of its sides or faces, there being a number of such recesses *a*², herein shown as formed in its outer side or face, and a corresponding number of recesses *a*³ formed in its inner side or face opposite the aforesaid recesses *a*². 35 Within the boundaries of said recesses the material is very thin, as indicated by dotted lines, Fig. 2, and consequently may be easily broken out or knocked out when desired, and the pieces, web, or films so knocked out correspond in area to the openings produced by 40 their removal. By disposing said thin portions at the bottoms of the recesses the liability of breaking the box when breaking out the holes is reduced to the minimum, and a 45 cleaner hole may be broken, as the metal is less liable to chip off at the edges, and, furthermore, visual indications are provided on the outside of the wall which indicate to the workmen just where to strike the blow. In 50 the side wall *b* of the shell similar recesses

are also provided, as many as may be desired, being located both inside and outside of the wall, and like thin portions, called "knock-out" portions, are consequently provided.

By referring to Fig. 2, *b*' *b*² represent the 55 recesses in the opposite sides or faces of the wall, and *b*³ represents the thin portion or knock-out portion.

The side wall *b* is oftentimes made circular, as shown in the drawings, and in such case 60 it has been difficult to secure a coupling thereto, for the reason that the seats upon the opposite sides or faces of said wall against which the members of said coupling abut are curved; but herein the wall is formed with 65 flat portions or faces, both inside and out, surrounding the several recesses *b*' *b*², and by so forming said side wall it will be seen that flat seats are provided, against which the members of the coupling will abut, which insures 70 a better joint.

c represents one of the flat faces which is provided inside of the wall *b*, it extending from top to bottom of the wall, and *c*' represents one of the flat faces provided outside 75 of the wall.

It is furthermore apparent that by providing flat faces or seats, as herein shown, the side wall *b* will be made thicker at said points, and such increase in thickness will be sufficient to enable a tap to operate and tap a hole, as 2, for a screw without the necessity of providing the shell with inwardly-projecting ears, which have heretofore been required for this purpose. 85

The coupling herein shown comprises a union *d* and a screw-threaded nipple *d*', and by referring to Fig. 2 it will be seen that said parts bear flat against the flat seats provided for them. 90

Heretofore the side wall has been made circular and a recess has been cast in its inner side, but in such case the bottom of the recess has been curved to correspond with the curvature of the said wall, and as a result a 95 piece having a curved face must be broken out, and in practice it is difficult to break out such a curved piece without breaking the box. Herein the bottom of the recess is formed flat instead of curved, as shown in Fig. 2, and 100

hence can be struck a severe blow with a peen or other suitable implement and effectively broken out without breaking the box. Thus the provision of flat knock-out portions in a 5 curved side wall is one of the important features of our invention.

We claim—

1. In a junction-box, a shell or case having a curved side wall formed with recesses both 10 inside and outside of its walls, disposed opposite each other and leaving a thin flat knock-out portion, substantially as described.
2. In a junction-box, a shell or case having a curved side wall formed with recesses and 15 with flat portions surrounding said recesses which provide flat seats against which the members of the coupling abut, substantially as described.
3. In a junction-box, a shell or case having a curved side wall formed with a recess and 20 with a thin flat knock-out portion at the bottom of said recess, substantially as described.
4. In a junction-box, a shell or case having a curved side wall formed upon its outer face 25 with flat bearing-surfaces below the surface of which are located flat knock-out portions, substantially as described.
5. In a junction-box, a shell or case having a curved side wall formed with one or more 30 thickened places including flat outer bearing-faces and flat knock-out portions, substantially as described.
6. In a junction-box, a shell or case having

a curved side wall formed with recesses both inside and out, and with flat portions surrounding said recesses both inside and out which provide flat seats against which the members of the coupling abut, substantially as described.

7. A knock-out box made in one piece and 40 having a curved flange formed with flat knock-out webs or films substantially corresponding in area to the openings produced by their removal.

8. A circular knock-out box made in one 45 piece and having a curved flange formed with flat knock-out webs or films set below its outer surface and substantially corresponding in area to the openings produced by their removal.

9. A circular knock-out box comprising a disk-shaped bottom and a circular flange, the 50 said bottom and flange being formed with flat knock-out webs or films set below their outer faces, and the outer surface of the flange being formed with flat bearing-surfaces below which the said flat knock-out webs or films are located.

In testimony whereof we have signed our names to this specification in the presence of 60 two subscribing witnesses.
